UNITED STATES PATENT OFFICE.

JOHN DAVIS SHIPMAN, OF SAN ANGELO, TEXAS.

SASH-FASTENER.

1,114,391.

Specification of Letters Patent.

Patented Oct. 20, 1914.

Application filed December 3, 1913. Serial No. 804,473.

To all whom it may concern:

Be it known that I, JOHN DAVIS SHIPMAN, a citizen of the United States, residing at San Angelo, in the county of Tom Green, and State of Texas, have invented new and useful Improvements in Sash-Fasteners, of which the following is a specification.

This invention relates to window sash fasteners, and its primary object is to provide a fastener of simple, reliable and efficient construction for locking the sash at any point in its path of movement upon the window frame.

10 A further object of the invention is to provide a sash fastener or lock which entirely avoids the use of springs or other parts liable to get out of order.

A still further object of the invention is to provide a sash fastener or lock including a gravity dog or pawl on the sash adapted to engage a rack upon the window frame, combined with means whereby the pawl may be retracted conveniently when the sash is elevated to release it from engagement with the rack and permit the adjustment of the sash.

The invention consists of the features of construction, combination and arrangement 30 of parts herein fully described and claimed, reference being had to the accompanying drawings, in which:

Figure 1 is an elevational view showing the application of the invention to a window frame and sash. Fig. 2 is a similar view illustrating the dog releasing action. Fig. 3 is a perspective view of the bracket and dog detached. Fig. 4 is a similar view of the rack.

40 Referring to the drawing, 1 designates a window sash, and 2 one of the sides of a window frame. Upon the said side 2 of the window frame is arranged a rack 3, preferably formed of a strip of sheet metal bent or offset at intervals throughout its length to provide keeper recesses or pockets 4, an inclined stop wall 5 at the top of each pocket, and an abutment wall or surface 6 at the bottom or lower end of the pocket. 45 Secured to the adjacent side of the window frame is a bracket plate 7, screwed or otherwise secured thereto and provided upon its outer face with a loop or housing 8, between which and the bracket plate extends a pin 9. 50 A gravity dog or pawl 10 is provided for interlocking engagement with the rack, and

is provided with a manipulating knob or handle 11. From the body portion of this dog extends a lug 12 which projects into the loop or housing 8 and is apertured for the passage of the pin 9, whereby the pawl or dog is pivotally mounted to swing in a vertical plane in an arc which is transverse to the plane of the side of the sash to which the dog is attached. The dog is also provided with a locking arm 13, which is curved downwardly and outwardly and formed in the upper surface of its extremity with a notch 14, the said extremity of the dog being adapted to fit within and engage the 70 pockets or recesses 4 of the rack. The dog body 10 is arranged on the inner side of the loop or housing 8, and the arm 13 curves downwardly and outwardly and extends across the bracket below said loop or housing. The weight of the dog is such as to cause it to normally drop by gravity to 75 throw its locking arm into engagement with one of the recesses or pockets of the rack.

It will be understood from the foregoing description that by means of the knob 11 the pawl may be swung upwardly, thereby withdrawing its arm 13 inwardly from engagement with the rack, allowing the window frame to be adjusted as desired. When the 80 locking arm enters a recess or pocket 4 its notched portion engages the wall 5 thereof, thus arresting upward movement of the sash, so that upon the release of the sash the arm will gravitate easily into engagement 85 with the underlying abutment surface 6 by which the sash will be locked against movement in either direction in adjusted position. The lower face of the dog is curved in such manner that when the dog is positively tilted 90 from retraction, the arm will slide easily off the surface 6 engaged thereby, thus preventing the dog from hanging or binding in the rack pocket. The downward or locking motion of the dog is limited by a contact of the 95 lug with the lower wall of the loop or housing, while the upward or retracted motion of the dog is limited by a guide loop or eye 100 projecting from the upper portion of the bracket. Through this loop or beyond is extended a retracting cord 16, which is attached at its upper end to the knob or handle 11, the lower end of the cord depending to a convenient position so that when the sash is elevated the operator may retract the latch 110 from below, thus avoiding the necessity of reaching up or standing upon a chair or

other object to manipulate the knob. If desired, a guide member 17 may be mounted upon the lower end of the bracket or upon the sash to hold the cord extended across the top of the housing 8 and out of the path of movement of the locking arm of the dog, and to otherwise maintain the cord in proper pendent position.

From the foregoing description, taken in connection with the drawing, it will be seen that my invention provides a sash fastener which is simple of construction, which is adapted to automatically lock by gravity and dispenses with the use of springs, whereby reliability of action is secured, and which is positive in operation and adapted to be conveniently manipulated to lock the sash in open, closed or any intermediate position, the advantages of which will be manifest.

I claim:

1. In combination with a rack, a fastener adapted for coöperation therewith, said fastener comprising a bracket plate, a gravity dog pivoted to the bracket plate and having

a lug projecting laterally therefrom, and a curved arm projecting downwardly and outwardly below said lug, a guide upon the bracket above the pivot of the dog, and a cord extending through said guide and connected with the body of the dog above the plane of the pivot.

2. In a sash fastener, a rack, a bracket plate, a gravity dog comprising a weighted body having a lug projecting laterally therefrom and pivoted to the bracket and a curved arm projecting therefrom downwardly and outwardly below said lug, an operating element connected with the dog body, a guide upon the body above the pivot of the dog, and a cord extending through said guide and connected with the body of the dog above the plane of the pivot.

In testimony whereof I affix my signature in presence of two witnesses.

JOHN DAVIS SHIPMAN.
